Attorney.

UNITED STATES PATENT OFFICE.

LOUIS F. DOELLINGER, OF WATERLOO, IOWA.

WRINGER ATTACHMENT.

1,375,784.

Specification of Letters Patent. Patented Apr. 26, 1921.

Application filed December 2, 1920. Serial No. 427,694.

To all whom it may concern:

Be it known that I, LOUIS F. DOELLINGER, a citizen of the United States of America, and a resident of Waterloo, Blackhawk county, Iowa, have invented certain new and useful Improvements in Wringer Attachments, of which the following is a specification.

My invention relates to improvements in wringer attachments, and the object of my improvement is to provide means for preventing clothes or the like from becoming enwrapped about rolls of a wringer and to render such means susceptible of good frictional contact with the rolls and self-adjusting vertically as required conformably to the operation of the rolls upon the clothes.

My invention herein also constitutes an improvement upon my wringer attachment patented April 6, 1920, No. 1,335,957.

The above object has been accomplished by the means which is hereinafter described and claimed, and which is illustrated in the accompanying drawings, in which Figure 1 is a perspective side elevation of a clothes-wringer equipped with my pivotally connected coacting devices for preventing the enwrapping of clothes about either roll; Fig. 2 is an enlarged perspective view of said coacting devices alone; Fig. 3 is a view, partly in end elevation and partly in cross-section of said coacting devices and wringer-rolls about which they are movably and removably mounted, and Fig. 4 is a perspective view of the clamping-means used to movably mount said devices upon a frame element of a wringer.

Similar numerals of reference denote similar parts throughout the several views.

40 My invention comprises two like coacting devices or hangers 1, on each end of a longitudinal fixed rod 4 in each case, the ends of each rod being fixed in its hanger a short distance above the lower end of the latter.

45 A pair of like but reversed hangers are placed next to each other at each end of the device, each hanger having its upper part curved over in an arched form terminating in a short end 2, the short end 2 of one hanger only of each reversed pair being pivotally connected to the other hanger of the same pair on a pintle 3. The inner arched parts of said pairs of hangers only are rigidly connected by a rod 6.

50 The rods 4 and 6 are preferably incased in a soft flexible tubular wrapping 5 and 7 re-

spectively, which as shown may be a relatively thick layer of soft cloth having a nap. The rod 6 is positioned medially upon the inner arched parts 3 of the inner hangers 60 and a flat body 8 is extended along the rod 6 and its wrapping to project vertically upward, and has in the middle of its length a vertical slot 11 enlarged circularly at its lower end 12 like an inverted key-hole. 65 This body or rigid plate 8 extends nearly the whole length of said rod 6 and its lower margin is bent to one side, providing a horizontal flange 9 which is secured by rivets 10 to the rod below. 70

When the above described wringer attachment is positioned as shown in Figs. 1 and 3 above and about the rolls 20 and 21 of a wringer 19, the longitudinal vertical plate 8 abuts upon and along a transverse frame 75 member of bar 18 of the wringer.

Referring to said Fig. 4, the numeral 13 denotes a short flat horizontal bar having its opposite ends bent upwardly at right angles at 14 and 16, said ends having threaded 80 openings to receive screws 15 and 17 respectively. Adjacent the raised end 16 the bar 13 is diminished in width at 23 by being notched at opposite sides.

The bar 13 may be inserted through the 85 eye 12 of the slot 11 to locate its narrowed part 23 to pass the latter part into and vertically along the slot 11 when the bar is moved upwardly to place its ends 14 and 16 along opposite faces of the frame-bar 18, 90 and the screws 15 and 17 may then be turned to removably secure the bar 13 to the bar 18.

The lower roll 21 of the wringer 19 is a soft rubber body mounted on a driven-shaft 22, and the latter may be positively rotated 95 by any desired means, such as by power-transmission mechanism operated by a motor, or by a hand-crank. The soft flexible wrappings 5 and 7 on the hanger members 4 and 6 respectively afford a yielding frictional contact with the rolls 21 and 20 respectively, preventing the working down or over of parts of clothes between the members 4 and 6, and said rolls, which might occur with bare rods. 100

The slotted standard plate 8 being freely movable vertically because of the loose connection to the fastening-bar 13 at the narrowed part 23, can yield upwardly with the roll 20 when an unusually thick part of 110 clothing is being passed between the rolls, without becoming relatively displaced from

the upper roll, thus causing the device to function perfectly at all times.

The hanger-members 1—2 may be otherwise associated or connected for relative movements, as combined with the other said improvements without departing from my invention.

Having described my invention, what I claim as new, and desire to secure by Letters 10 Patent, is:

- 15 1. A device of the character described, comprising pivotally connected coacting hangers supported removably and vertically movable on a relatively fixed element of a wringer above the upper roll of a pair of rolls, and having deflector-members respectively extended along the top of the upper roll and along opposite sides of the lower roll.
- 20 2. A device of the character described, comprising pivotally connected coacting hangers positioned above and about opposite sides of a pair of wringer rolls, said hangers

having deflector-members respectively extended along the top of the upper roll and 25 along opposite sides of the lower roll, a vertically slotted standard fixed upon the deflector-member which is extended along the upper roll, and clamping-means traversing the slot in said standard and the latter movable vertically therealong, said clamping-means being releasably secured to a relatively fixed element of the wringer.

3. A device of the character described, comprising movably connected coacting 35 hangers supported removably on a wringer above the upper roll thereof and having deflector-members respectively extended along the top of the upper roll and along opposite sides of the lower roll, and soft flexible 40 wrappings mounted around said deflector-members to contact frictionally and yieldingly with said rolls.

Signed at Waterloo, Iowa, this 4th day of Nov. 1920.

LOUIS F. DOELLINGER.
